UNITED STATES PATENT OFFICE.

PETER OSTERSPEY, OF MECHERNICH, PRUSSIA, ASSIGNOR TO ADOLPHUS MEIER & CO., OF ST. LOUIS, MISSOURI.

IMPROVEMENT IN ORE-SEPARATORS.

Specification forming part of Letters Patent No. 170,890, dated December 7, 1875; application filed September 27, 1875.

To all whom it may concern:

Be it known that I, PETER OSTERSPEY, of Mechernich, in the Kingdom of Prussia, have invented an Improved Ore-Separator, of which the following is a specification:

This invention relates to the class of ore and mineral separators, washers, &c., and specially is an improvement on the well-known "siphon-washers" for the same purpose. The siphon-washers, as ordinarily used, consist chiefly of the following construction: A main vessel, having a screen-bottom, the opening in which is controlled by a plug or valve, operated from the under side by a lever. A side pipe supplies fresh water under this screen-bottom of the separator. At top is a trough for conveying the crushed or granulated crude ore or minerals, with a current of water, into the separator. Further, surrounding the top of the separator is an extra trough for receiving that part of the product which, by reason of less specific gravity, is washed over the sides of the separator.

When a sufficient amount of heavy material has settled on the sieve the operator opens the valve, which allows the greater portion of the heavy product to escape; then closes the valve to allow a repeated accumulation to take place on the sieve-bottom. The current of fresh water entering below encounters the crushed mineral falling from the trough, and while the heavy particles fall the lighter ones are carried up and over the sides of the separator by this current. Further, this current depends on the head of water in the supply-pipe for its velocity and pressure, both of which are increased as the free area is decreased by the accumulation of heavy mineral on and over the screen-bottom. They will both be greater immediately before opening the valve than just after opening. It is, therefore, apparent that great skill, care, and observance must be exercised to alternately open and close the valve at required times, or to so regulate the opening and closing of the valve that this variation in velocity and pressure may not become too great, which it is difficult for the most skillful operator to do, consequently to insure accuracy and uniformity of separation. Further, in machines of this

class it is necessary that a certain quantity of the heavy mineral be always kept on the sieve-bottom and suspended in the rising current, in order to equalize velocity in the middle and sides, and prevent a welling or spouting up at a few points. Only when the whole of any cross-section shows nearly uniform velocity can correct and uniform separation be attained.

To remedy the defects enumerated, and which render the said machines imperfect and unsatisfactory in their operation, is the main object of my invention.

My invention takes into consideration and utilizes the weight of the minerals suspended on the rising column of water, and which has heretofore not been considered, though known as a disturbing influence. The nature of my invention can, therefore, be stated to consist of an automatic mechanism, as will hereafter more fully appear, by means whereof the alternate opening and closing of the valve takes place at such intervals as may be necessary, to insure at all times a sufficient quantity of heavy minerals on the sieve and in suspense in the ascending column of water, and never too much or too little, thus achieving uniform velocity of this current.

Of the drawing, Figure 1 is a sectional elevation on line *x y* of Fig. 2. Fig. 2 is a top plan.

A is a suitably-constructed frame, in which the working parts of the apparatus are mounted. I provide this frame with the part division-walls *A*¹ *A*², to form the water-compartments *B* *C*, as shown in Figs. 1 and 2; the compartment *B* being to serve as a fresh-water-supply chamber, and that of *C* as a reservoir, for the purpose hereafter to appear. Properly supported within the frame parts *A* *A*¹ is the chamber or separator *D*, the bottom of which consists of a screen or grating, *d*, as ordinary. In communication with the opening in the grating *d* I provide a pipe, *E*, which, by its branch, communicates with an exterior trough, *E'*. The lower mouth of the pipe *E* is controlled by a plug, *e*, all shown in Fig. 1. The compartment *B* has free communication to the compartment *C*, and both said compartments further freely communicate with the screen-bottom *d* of the separator, as shown in

Fig. 1. F is the plug or valve fitted in the opening in the screen-bottom d. The stem f of the valve I have pivoted at f' to a hand-lever, G; this is pivoted at g to a support top of the frame A. (See Figs. 1 and 2.) The lever G I arrange to extend within reach of the stem h of a float, H, which I provide to operate in the compartment C. (See Fig. 1.) The lever G can be pivoted in any of the series of the holes h¹ in the stem of the float. By this means the operation of these parts can be made to control the opening and closing action of the valve at any desired stage of the washing, and as stated to be in the nature of my invention. h² is a guide-bar to guide the motion of the hand-lever. The frame at I forms the feed-trough.

The parts thus constructed and arranged operate as follows: The crushed crude materials are carried by a current of water through the trough I into the compartment D. The compartment B receives the fresh water entering through an opening at i, and which can be provided with a scale to enable the operator to regulate and measure the water quantity. When the water first enters B, and before any mineral is supplied in the separator, the water-levels in B and D are nearly the same. As soon, however, as the heavy minerals begin to accumulate on and over the grating d a back pressure on the water in B causes the water to rise higher in B and C, raising the float H, and consequently opening the valve F at just such a stage of the washing as may be desirable. A portion of the heavy mineral then escapes through the pipe E into the trough E', and the water again falls in B and C; also, the float H falls and the valve F closes. It is evident that the

continual opening and closing of the valve F by this automatic contrivance can be readily regulated; that, no matter what may be the specific gravity of the material or its quantity, the velocity of the rising current of water in D and quantity of heavy mineral on the sieve d may be kept uniform—in other words, the separation by specific gravity can be thus kept in just such limits of accuracy as may be required. By placing other exactly similar machines in connection with the trough I, the process of washing can be repeated as often as required, and the most perfect separation attained.

What I claim is—

1. In combination with a mineral separator or washer, D, the water-compartments B C, the float H, connected to a lever, G, carrying the valve F, by means whereof the weight of the minerals suspended in the separator is utilized to produce a back pressure of the water-column in C, to automatically open the said valve, as and for the purpose set forth.

2. An operating automatic mechanism, consisting of the water-compartments B C, the latter having a float, H, connected to a lever, G, carrying a valve, F, the pipes E, trough E', all said parts being combined with a separator of the character herein shown and described, and by means whereof the alternate opening and closing of said valve F is accomplished, in the manner set forth.

In testimony of said invention, I have hereunto set my hand.

PETER OSTERSPEY.
